FREDERICK F. CORNELL, JR., AND EDWIN M. WIGHT, OF NEW YORK, N. Y.

Letters Patent No. 61,719, dated February 5, 1867.

IMPROVEMENT IN PRESS FOR COMPRESSING BALES ALREADY FORMED.

The Schedule referred to in these Letters Patent and making part of the same.

TO ALL WHOM IT MAY CONCERN:

Be it known that we, FREDERICK F. CORNELL, Jr., and EDWIN M. WIGHT, both of the city, county, and State of New York, have invented certain new and useful Improvements in that Class of Presses designed for Compressing Bales already Formed, or for pressing goods or substances that require no box or press-chamber to retain them in position while being subjected to compression.

The objects and designs of our invention are, first, to secure in a press not provided with a permanent press-box or bale-chamber, a new and useful method of construction by means of which the frame usually required to receive the resistance occasioned by the action of the toggle-joints or levers upon the platen, may be entirely dispensed with; second, to obtain a convenient arrangement of the toggle-joints and levers above the head-beams of the press, and to suspend the platen by rods or bars passing down from the shanks of the levers and through or between said head-beams to connect with the same; third, to support said head-beams and the superincumbent toggle-joints and levers by posts, so arranged that they shall serve as guides to control the motion of the platen, and also secure the proper relative position between the said head-beams and the sills of the press; fourth, to so construct the levers used for operating the press, that when the toggle-joints are open to the greatest extent allowed by their arrangement, a horizontal plane passing longitudinally through the sills of the press would cut the lower ends of each of said levers at the points where power is applied to draw them down; fifth, a new and useful method of governing the motion of the upper ends or shanks of the toggle-levers, and of retaining the draw-rods of the platen in a perpendicular position by means of a vertical guide, placed above and over the centre of the press, and controlling a slide which is connected to each of the levers and is retained equally distant from each by horizontal bars, the levers being also permanently connected to each other by means of said bars; sixth, providing the lower ends of the draw-rods at either end of the press with stirrups to receive the ends of the lifting beam, or beams of the platen, and in and upon which they may rest and move loosely, so that by the introduction of suitable blocks of the required thickness, between the foot of the stirrups at either end, and the said beam or beams, or by any other suitable mechanical device, which will increase or diminish, as required, the distance between the said stirrups and the ends of the lifting beam or beams before mentioned, any required height may be given to the bale when the toggle-joints are open to their greatest extent.

The following is a full and exact description of our invention, so that those skilled in the art may be enabled to make and use the same. In the accompanying drawings—

Figure 1 is a vertical section of the press taken longitudinally in the line $x x$, of fig. 2.

Figure 2 is a transverse section of the press taken in the line $y y$ of fig. 1.

Figure 3 is a horizontal section taken in the line $z z$ of fig. 1.

The same letters are used to designate the same parts in each of the figures.

In constructing this new form of press, we securely frame together the ground sills A A, in such a manner that they may receive the guide sheaves a a, b b, and resist any pressure that may be exerted upon them by means of the chains c c, and also serve the further purpose of supporting the entire superstructure of the press. At suitable distances apart to receive the bale or substance to be pressed, we erect the four posts B B B B, two on either sill, and on the upper ends of said posts place the head-beams C C, to which are securely fastened the necessary facings, braces, &c., to form a secure and perfect head-block, and securing the whole structure firmly together by the girt-bolts d d d d. Longitudinally between said posts we place the lifting beam D of the platen, which is of such a length as to extend through or nearly through the openings between them, and upon the upper side of said lifting beam we place the facings of the platen so as to conform to the facings of the head-block, and extend them through between the posts B B B B, making notches in the same at e e e e, so that the said posts may serve as guides, and the edges of the facing or the main timbers of the platen perform the duty of slides against said posts to keep the platen from swinging when under pressure. On the upper faces of the head-beams C C, or the corresponding portion of the head-block, over the ends of the posts B B B B, we locate the fixed fulcrum points of the radii F F F F of the toggle-levers E E, which points are marked f f f f, and connect the said radii to their respective toggle-levers by the centre pins g g, which are placed in the levers at a distance from the shank pins h h equal to the length of the radii; said levers being extended downward from said centre pins a distance equal to the height of said centre pins, when the radii are brought to a vertical

position above the lower faces of the ground sills A A. The shank pins *h h* pass through eyes in the upper end of the draw-rods G G G G, which have their lower ends provided with or securely fastened to their respective stirrups, *k* and *l*, upon which the lifting-beam D, or the blocks *i i*, supporting the same, securely rest. Said shank pins also pass through and scive to connect to the levers the horizontal bars H H, which retain the shanks of said levers at a distance from each other equal to the distance between the fulcrum points of their radii, which is the same as that between the stirrups *k* and *l*. Midway between the shank pins *h h* we rigidly attach to the horizontal bars H H the slide I, which plays loosely between the guides K K, which are attached to the head-block or beams of the press, and secured against motion under lateral pressure by means of the guy-rods *m m*. To the lower ends of the levers we attach ropes or chains, which pass under and around the guide-sheaves *a a*, *b b*, and are thus delivered to the capstan, or they may be operated in any other convenient way.

The operation of the press is as follows: The height of the finished compressed mass having been determined by the introduction between the stirrups *k* and *l*, and the lifting beam D, of the blocks *i i* of the required thickness, (sets of blocks of various thickness being furnished with the press,) the bale or material to be pressed is placed upon the platen; and power being applied at the outer ends of the chains *c c*, to draw them from the sills A A, by means of a capstan or any other desirable method, the lower ends of the levers are caused to move inward towards the ends of the sills, thus turning them on their centre pins *g g*, and causing the shank, with the pins *h h* attached, to ascend, thus drawing on the rods G G G G, which, by the connections before explained elevate the platen, which presses on the bale or material which is again firmly resisted by the head-block until it has been reduced to the required density. The shanks of the levers, while ascending, are firmly controlled by the slide I moving freely between the guides K K, and acting upon said shanks by means of the horizontal bars H H, which retain their motion in right and perpendicular lines.

The advantages we claim for this mode of construction are, that we entirely dispense with the cumbersome frame usually necessary to retain the material, and the compressing mechanism in the proper juxtaposition during the process of pressing; again, that by causing the compressing mechanism on the one side of the head-beams or head-block to operate with a power which is equally balanced by the resistance of the material on the platen on the other side of said head-beams or head-blocks, the strain on the press is greatly diminished, and much cost and material can be saved in the construction; also that by the arrangement of the platen and the draw-rods, by means of which the height of the compressed mass may be varied, the great and only valid objection to the use of levers for such purposes is entirely removed; and lastly we secure a perfect control over the movements of each of the levers by means of a slide and guide which regulate their motion.

What we claim as our invention, and desire to secure by Letters Patent, is—

1. The use, in a press designed for the compressing of bales already formed, or of goods requiring no press-box to retain them in position between the platen and the head-block, and not provided with sides or ends for the purpose of forming such chamber or press-box, of toggle-levers, the fixed fulcrum points of whose radii are located above and upon the head-block or head-beams of the press.

2. The use, in a toggle-lever press not provided with permanent sides or ends, for the purpose of forming a press-chamber, of a platen suspended by means of rods or bars passing down through the head-block, or between the head-beams thereof from the ends or shanks of toggle-levers located on and above said head-block or the beams thereof.

3. The use, in a toggle-lever press not provided with permanent sides or ends, of posts located, two at either end, and so arranged that while serving as supports for the head-block, and its superincumbent weights, they shall also act as guides to retain the motion of the platen in right lines by engaging with suitable notches or slides in the same, substantially as hereinbefore described.

4. The use, in a toggle-lever press having the fixed fulcrum points of the radii of the levers thereof located on and above the head-block or the beams thereof, of a vertical guide attached to the centre of said head-block, and furnished with a slide provided with horizontal bars attached thereto, and extending to and connected by joints with the shanks of the toggle-levers on either side, and so arranged as to prevent the same from altering their relative position, and to retain their motion in perpendicular and parallel lines when operating the platen.

5. In a press having a platen suspended from toggle-levers located above, and having the fixed fulcrum points of their radii resting upon the head-block or the head-beams of the press, extending the lower portions of said levers downwards from the centre pins a sufficient distance to allow the moving power to be applied thereto at points *n n*, whose distance from the centre pins *g g*, (when the radii are brought into a perpendicular position,) shall be equal to the elevation of said centre pins above the lower faces of the guide-sheaves *a a* located in the ground sills of the press.

6. The sheaves *a a*, *b b*, *c c*, chains *e e*, levers *E E*, draw-rods G G G G, horizontal connecting bars H H, shank pins *h h*, and slide I, all arranged and combined as and for the purposes hereinbefore specified.
